UNITED STATES PATENT OFFICE

JOSEPH H. ADDLER, OF BROOKLYN, NEW YORK, ASSIGNOR TO PULLCLEAN MANUFACTURING CORPORATION, OF BRIDGEPORT, CONNECTICUT, A CORPORATION OF DELAWARE

TOWEL CABINET

Application filed December 7, 1929. Serial No. 412,340.

This invention relates to towel cabinets of the type adapted to contain a so-called "continuous" towel, that is, a long length of towel, usually in roll form, which is adapted 5 to be drawn outwardly through an opening in the cabinet in suitable predetermined lengths for drying purposes. This type of cabinet is usually provided with a roller mounted therein in position to be engaged 10 and rotated by the towel as the latter is withdrawn from the cabinet, the said roller being effective, by the alternate stopping and releasing of the same, to control the feed of the towel from the cabinet.

15 The object of the present invention is to provide a simple and efficient means for effecting the stopping and releasing of the said feed controlling roller. This object is attained by the new and novel construction 20 and arrangement of parts as hereinafter described and claimed and as illustrated in the accompanying drawings, in which—

Fig. 1 is an end elevation of a cabinet equipped with my invention, with the outer 25 casing in section.

Fig. 2 is an enlarged sectional detail, with the section taken on line 2—2 of Fig. 5, showing the feed roller stopping and releasing mechanism.

30 Figs. 3 and 4 are similar views showing different positions of the parts.

Fig. 5 is a front view of a part of the cabinet with the outer casing broken away adjacent the feed roller stopping and releasing 35 mechanism.

Fig. 6 is a detail showing in top plan the housing for the stop releasing device and the stop member projecting therefrom; also in broken lines the stop releasing device 40 itself.

The cabinet, which may be of any desired construction or design, is here shown as comprising an outer casing formed in two sections 2 and 3, the front section 3 being hinged at 1 or its vertical edges to the rear section 2, as at 4, whereby the casing may be opened to permit of ready access to the interior thereof.

50 Located within the casing adjacent its opposite ends are a pair of frame or bracket

plates for the support of certain parts of the towel controlling mechanism to be presently described. Only one of these bracket plates, indicated at 5, is here shown, the same being secured in position by suitable fastening means, such as the bolts 6. The opposite bracket plate (not shown) is of like construction and similarly fastened in position.

Carried by these bracket plates is a suitable shelf 7 upon which is supported the roll 55 of clean towelling, indicated at 7. When so supported, the leading end of the towel is led from the front side of the roll downwardly and partially around a feed roller 8, suitably journalled in the end brackets, from thence forwardly through an opening 9 in the front wall of the casing to and over a guide roller 10, which latter is journalled in extensions of the bracket plates which project through the opening 9 in the casing to 60 support the roller at the front side thereof. From this guide roller 10, the towel depends in loop form, as at 7, in convenient position for use; the towel at the rear side of the loop passing backwardly through the opening 9 65 to a usual form of take-up or re-winding device comprising a pair of rollers 11 and 12, between which the towel is passed, the roller 11 being operated to pull the engaged 70 towel into the cabinet and rewind it upon the roller 12. The roller 11 is operated in this way from the feed roller 8 when the latter is rotated by the frictional engagement therewith of the towel upon the withdrawal of the latter from the cabinet; the 75 roller 11 being operated to pull the engaged towel into the cabinet and rewind it upon the roller 12. The roller 11 is operated in this way from the feed roller 8 when the latter is rotated by the frictional engagement therewith of the towel upon the withdrawal of the latter from the cabinet; the 80 connection between the rollers being the usual chain and sprocket connection employed in these cabinets, such as the sprockets 15 and 16 rigidly attached to the ends of the rollers and engaged by the connecting 85 sprocket chain 17.

As hereinbefore referred to, it is an object of the present invention to provide a simple and effective means for controlling the feed or delivery of the clean towel whereby its withdrawal from the cabinet will be in predetermined lengths. This I accomplish by the provision of means for automatically stopping the roller 8 once upon each rotation thereof and thereby stopping the out- 90 95 100

ward feeding or withdrawal of the towel; it being understood that the friction between the towel and the roller is such as to prevent movement of the towel independently of the roller under ordinary pulling strains such as exerted in the normal use of the cabinet.

The improved means for stopping rotation of the roller 8 as referred to comprises a pin or bolt 20 slidably mounted in a transverse socket or bore 21 formed in a housing block 22 on the outer end of the sprocket wheel 15 carried by said roller 8; this bolt being freely slideable in the socket 21 for movement transversely of the roller and being limited in its movement in one direction by the contact of its inner end with a stop member 23 within the socket, and in the opposite direction, or outwardly of the socket, by the contact of a stop shoulder 24 thereon with a stop shoulder 25 in the wall of the socket 21, as shown in Figs. 2, 3 and 4.

When a length of towel is drawn out from the cabinet, thereby causing rotation of the engaged roller 8, this bolt 20 will slide outwardly from the block 22 under the action of gravity as it moves downwardly from a horizontal position, so as to project its outer end beyond the block, as shown in Fig. 4. During continued rotation of the roller, the extreme outer end of the bolt, indicated at 26, is brought into contact with a fixed stop 27, as shown by full lines in Fig. 1 and by broken lines in Fig. 3, and so stops rotation of the roller and thereby further withdrawal of the towel. Subsequently, to obtain another length of towel, the bolt is released from the stop 27 to permit another rotation of the roller. For effecting such release of the bolt, a releasing device is provided in the form of a push-button 35 slidably supported in a housing block 36 on the inner wall of the casing, with its head at the outer side of the casing for convenient engagement by the user and with its inner end or stem adapted for pressing engagement with the bolt. This releasing device, however, differs from similar devices in the prior art in that it is located above the bolt engaging stop 27 instead of below said stop. Because of such different location of the releasing device, it becomes necessary to provide a different construction of bolt than heretofore in order that it may be engaged and moved back to releasing position by the releasing device. This construction I provide by forming the bolt with a face 40 set back from its stop engaging surface 26 sufficiently to permit of its movement upwardly past the stop when the bolt is in its outwardly projected position, as in Figs. 1 and 4, and at the same time giving said face sufficient height above the surface 26 so that it will assume a position opposite the releasing device for engagement thereby when the bolt has been brought to a stop with its surface 26 in contact with the stop 27.

With the described construction, when the bolt has been brought into engagement with the stop 27, as shown in Fig. 1, the feed roller will be stopped in its rotating movement. To release the roller for the obtainment of another length of towel, the user pushes the button 35 inwardly against the oppositely located face 40 of the bolt and thereby forces the latter backwardly to a position against the member 23 and with its stop surface 26 disengaged from the stop 27, as clearly shown in Fig. 2. Following such operation of the push button and upon its release by the user, it is automatically returned to its normal position under the action of a coiled spring 50. The feed roller is now free to turn and permit of the withdrawal of another length of towel, the bolt remaining in its retracted position when being moved past the stop, as shown in Fig. 3, and remaining in such position until, during the continued rotation of the roller it reaches a position below the horizontal, as shown in Fig. 4, when it will again gravitate outwardly from the block to project its end into position for engagement with the stop 27, as shown by broken lines in Fig. 3 and by full lines in Fig. 1, as hereinbefore referred to.

The housing block 36 for the releasing device is here shown as having a pair of perforated ears 51, 51, by which it is secured on the inner wall of the casing at one end thereof by fastening screws 52. The releasing device is supported in this block in its normal outwardly projected position, as shown in Figs. 1, 3 and 4, by means of the coiled spring 50 which is mounted on the stem of the device with one end bearing against a shoulder 53 on the stem and its opposite end bearing against a stationary shoulder in the block itself (see Fig. 2). An enlarged head 55 at the inner end of the stem engages the inner wall of the block to limit the outward thrust of the device under the action of the spring 50.

The bolt engaging stop 27 may be formed and positioned in any suitable or desired way, the same, as best shown in Fig. 2, being formed as an integral part of the block 36 and projecting forwardly at the lower side thereof into the path of the bolt.

What I claim is:

1. In a towel cabinet, the combination of a towel feed-controlling roller, a stop, a slidably mounted bolt carried by said roller adapted to be projected from its support during rotation of the roller into position for engagement with said stop at one side thereof, and a bolt releasing device mounted at the opposite side of said stop, the releasing device and bolt having faces positioned opposite each other when the bolt is in engagement with the stop whereby the releasing device may engage the bolt to release it from the stop.

2. In a towel cabinet, the combination of

a towel feed-controlling roller, a stop, a slidably mounted bolt carried by said roller adapted to be projected from its support during rotation of the roller into position
5 for engagement with said stop at the under side thereof, and a bolt releasing device slidably mounted at the upper side of said stop, the said bolt, when in engagement with the stop, having a face positioned above the latter
10 for engagement by the releasing device to release the bolt from the stop.

3. In a towel cabinet, the combination of a towel feed-controlling roller, a stop, a freely slidable bolt carried by said roller adapted
15 to be projected by gravity from its support during rotation of the roller into position for engagement with said stop at the under side thereof, and a bolt releasing device slidably mounted at the upper side of said stop, the
20 said bolt having a face for engagement by the releasing device which is set back from its stop engaging surface for movement past and above the stop and into position opposite the releasing device for engagement thereby
25 when the bolt is brought into contact with the stop.

In testimony whereof I affix my signature.
JOSEPH H. ADDLER.
